BEVERAGE DISPENSING MACHINE

Ford Se Bastian, Glen Ellyn, Ill., assignor to The Silex Company, Chicago, Ill., a corporation of Connecticut

Application February 6, 1957, Serial No. 44,771

Term of patent 14 years

(Cl. D52—3)

Fig. 1.

Fig. 2.

Fig. 1 is a perspective view of a beverage dispensing machine, showing my new design; and

Fig. 2 is a rear elevational view thereof.

The opposite side of the dispensing machine is substantially the same in appearance as the side shown.

I claim:

The ornamental design for a beverage dispensing machine, as shown and described.
